PUMPING APPARATUS

William J. Conery, Ashland, Ohio, assignor to
 The F. E. Meyers & Bro. Co., Ashland, Ohio, a
 corporation of Ohio

Application April 7, 1949, Serial No. 85,983

5 Claims. (Cl. 103—5)

1

The present invention relates to pumping apparatus or systems, particularly those of the jet type, and is concerned primarily with pumps that are adapted to be converted from shallow to deep well or vice-versa with simple changes in the connections.

Various types of combined jet-centrifugal pumps are being produced by pump manufacturers and intended to be converted from deep to shallow well or vice-versa but the structure and arrangement of parts are such that the conversion not only takes considerable time, but also involves additional apparatus of an expensive character in making the substitution or replacement of parts during the converting operation. Moreover, in those pumps in which the jet unit is contained in the combined air separator priming chamber difficulty has been experienced in making adequate provision for connecting the air volume control to the suction side of the centrifugal pump, particularly when it becomes necessary to change the operation of the pump over from shallow well to deep well.

In an attempt to avoid this difficulty the art has either removed the jet pump to a position exterior of the priming chamber where it is more accessible, or else the automatic air volume control connection has been left off entirely. However, when the jet pump is positioned remote from the chamber and is not contained within the chamber, the latter necessarily must be made relatively small in order that the overall dimensions of the pump assembly will not be unduly large and in this case the degree of air separation is reduced in corresponding amount. On the other hand, when the automatic air volume control is omitted entirely, the necessary air cushioning effect at the pneumatic pressure tank cannot be obtained so that the system does not operate satisfactorily.

Still another difficulty found in manufacturing and operation of pumps of this character, particularly when designed for optional shallow or deep well use, is that the individual parts cannot be readily removed for inspection or replacement without also removing the main portions of the pump assembly which might offer difficulty to the average user where the pump is permanently located over a well. The elements to be removed are often quite heavy and cumbersome, particularly when forming part of a relatively large pump, so that the inspection of the pump as well as the removal of any parts for quick conversion represents considerable work.

The primary object of the present invention is

2

to provide a pump of the jet-centrifugal type adapted for both shallow and deep well use and in which the conversion from shallow to deep well and vice-versa is accomplished with a minimum of effort and involves the substitution of the simplest type of parts.

Another object is to provide a pump of the type noted and in which the jet unit is contained within a combined, totally enclosed air separator-priming chamber and yet the jet pump can be removed as a unit and an accessory substituted therefor for use when the pump is arranged for deep well operation.

Another object is to provide a pump of the character described with a combined air separator-priming chamber and in which the nozzle and diffuser elements of the jet pump are attached together in proper spacing within the chamber and can be removed as a unit for conversion to deep well use without having to remove the chamber.

Another object is to provide an improved pump of the type noted having a relatively large combined air separator-priming chamber containing a detachable jet pump unit and in which the only change necessary for converting the pump to deep well operation is the substitution of a tubular member for the jet pump unit, the change being made without disturbing the chamber other than removing the jet pump unit.

Still another object is to provide an improved convertible pump having a combined air separating and priming chamber containing a jet pump unit, the latter being presented to the suction side of the centrifugal pump unit together with a device for introducing air to the centrifugal pump.

Still another object is to provide an improved pump, convertible from shallow to deep well and vice-versa, having a combined air separating and priming chamber containing a jet pump unit presented to the suction side of a centrifugal pump unit, together with a device for introducing air to the centrifugal pump and in which conversion of the pump from shallow to deep well can be accomplished without interfering in any way with the air introducing device.

Another object is to provide a pump of the type noted having a combined air separating and priming chamber containing a jet pump, the invention being characterized by the use of an air inlet device connected to the suction inlet of the centrifugal pump and removable with the pump from the chamber when it is desired to inspect or replace any of the parts.

A further object is to provide an improved pump of the type referred to and having a combined air separator and priming chamber containing a jet pump with the suction inlet of the jet pump connected to the suction pipe from the well and the nozzle communicating with the chamber, the invention being characterized by the facility of being able to remove the jet pump without having to remove the chamber when conversion to deep well use is desired.

Another object of my invention is to provide a pumping system in which the pressure or centrifugal pump is mounted with its axis of rotation horizontal and which comprises the combination of a jet pump, a pressure pump, and a combined air separating and priming chamber containing each of the jet and pressure pumps so arranged that when converting to deep well use the jet pump parts can be removed as a unit from the chamber without disturbing either the chamber or the pressure pump.

A further object of the invention is to provide a pumping system in which the pressure or centrifugal pump is mounted with its axis of rotation horizontal and discharging into a chamber of relatively large size containing a jet pump unit in communication with the chamber and so constructed and arranged that the jet pump unit can be removed from the chamber at one side thereof and the pressure pump can be removed from the chamber at the other side thereof.

The general and final object of my invention is to provide a jet type pumping apparatus or system including a combined air separator-priming chamber of relatively large size and which may be converted from a shallow well pumping system to a deep well pumping system or vice-versa at considerably less expense than the apparatus or systems on the market and readily accomplished by a farmer or other mechanically unskilled person without necessitating the dismantling of the pump.

Other objects and advantages of my invention will be apparent as the specification is perused in connection with the accompanying drawings in which:

Figure 1 represents a side elevational view, partly in section, of the general assembly of the improved pump when set up for shallow well operation;

Figure 2 is a sectional detailed view, partly in elevation, of the air volume control apparatus adapted for use in the pump shown in Figure 1;

Figure 3 is a sectional view of the jet pump unit used in the shallow installation;

Figure 4 is an elevational view looking toward the left-hand end of the jet pump shown in Figure 3;

Figure 5 is an elevational view looking toward the right-hand end of the jet pump shown in Figure 3;

Figure 6 is a sectional view of a detail coupling used in place of the jet pump of Figure 3 when the main pump assembly is being converted to deep well operation;

Figure 7 is an elevational view looking toward the left-hand end of the device shown in Figure 6;

Figure 8 shows diagrammatically the general pump assembly when set up for shallow well use; and

Figure 9 represents, in part diagrammatically and partly in section, the pump assembly when arranged for deep well use.

Referring more particularly to Figure 1, the pump assembly includes the three main parts, the motor generally designated at 1, the motor

bracket designated at 2 and the combined air separating-priming chamber generally indicated at 3. The motor may be of any suitable type and has attached thereto a pressure operated switch 4 which serves to interrupt the electrical circuit (not shown) to the motor when the pressure in the chamber 3 becomes greater than a predetermined amount as will be described more fully hereinafter. The mounting flange of the motor is attached to the bracket 2 by means of bolts 5 which pass through bossed portions of the bracket into the motor mounting flange.

The bracket constitutes a hollow casting provided with spaced ribs 6 and terminating at the bottom in feet 7 which may be bolted to a foundation at the position of the heavy washers 8. There are open spaces between the ribs 6 and these spaces are temporarily closed to prevent dust from entering by means of a sheet steel flexible covering 9 which is positioned between shoulders 10 and the ends of which are attached to the bracket by means of screws 11.

The motor is provided with a shaft 12 which is snugly received by an apertured shoulder 13 having set screws 14, this shoulder being formed by an extension of an impeller shaft 15 which terminates in a threaded plug portion 16. The shaft 15 extends through a suitable seal 17 and carries at its end an impeller 18 of any suitable and well-known type which constitutes a pressure pump. This impeller contains vanes 19 and a suction inlet conduit 20. There is a pump casing 21 positioned about the impeller, the right-hand half of the casing terminating in a hub 22 for receiving the seal member 17. This portion of the pump casing may be formed integral with the motor bracket 2 in one complete casting as indicated on the drawings. The other half of the casing terminates in a threaded shoulder 23.

This shoulder portion is provided with an annular recess 24 for receiving a rubber bearing 25 immediately surrounding the suction inlet member 20 of the pump. The peripheral portion of the left-hand casing member terminates in an annular vane plate which provides spiral passageways for the water leaving the impeller and discharges this water through suitably positioned ports (not shown) into the chamber 3. The left-hand casing half can be detachably secured to the right-hand portion of the casing and therefore to the motor bracket 2 by means of suitably positioned bolts 27.

The combined air separator-priming chamber 3 may be formed of a relatively large hollow casting 28 which is completely closed except for relatively small threaded openings for receiving pipes, as will be explained hereinafter, and also except for a centrally disposed opening 29 in the right-hand wall for snugly receiving a shouldered surface 30 of the motor bracket 2. The latter can be detachably secured to the wall of the casing by means of suitably positioned bolts 31 which bear against bosses 32 formed on the interior of the bracket casting.

The casting 28 is provided with ribs indicated at 33 for strengthening purposes. A threaded bore 34 may be provided at the top of the casting for receiving a pressure or compound gauge 35 having a threaded coupling. The service or discharge pipe 36 for the pump is taken from the upper side of the chamber 3, a threaded opening 37 being provided for this purpose.

The casting 28 at the left-hand end (as shown in Figure 1) is provided with a thickened portion 38 which surrounds a threaded bore 39. This

bore is adapted detachably to receive the threaded shank 40 of a jet pump which is comprised essentially of a nozzle 41 and a diffuser or venturi 42 as is well-known in the art. The details of the jet pump unit are shown more clearly in Figures 3, 4 and 5.

The body of the jet pump unit, including the shank portion 40, may comprise an enlarged hexagon-shaped extension or fitting 43 having a threaded countersunk opening 44 for receiving the threaded end of a pipe 45 (Figure 1) constituting the suction conduit which normally passes down into the well as indicated in Figure 8. If desired, a foot valve may be employed at the bottom of the suction pipe in the well in order to maintain the priming chamber 3 filled with water. The shank portion 40 of the jet pump unit is provided with a reentrant passageway 46 (Figure 3) of curvilinear shape and terminating in a circular opening 47 which is in line with the interior of the nozzle element 41.

The latter is threadedly received as indicated at 48 by the reentrant portion of the member 40 and a hexagon collar 49 may be provided so as to assist in tightening the nozzle element into the body 40. The tip 50 of the nozzle is of smaller size than the inwardly flaring portion 51 of the diffuser 42 so as to leave an annular space around the outer surface of the nozzle. This space communicates through a semi-circular passageway 52 with the opening 44 so that a free passage is established between the suction pipe 45 and the interior of the diffuser 42 around the nozzle 41. In addition, communication is also established between the interior of the chamber 3 and the interior of the nozzle 41 through the passageway 46. In order that the water flowing from the chamber 3 to the nozzle interior is directed gently toward the passageway 46, the chamber 3 may be provided with a slanted or tapering surface indicated at 53, thus insuring no eddy current or intense friction losses.

The diffuser 42 is provided with an annular projection 54 having a circular groove 55 for receiving a washer 56, preferably of circular cross-sectional area. The projection 54 provides an abutment 57 for making a tight joint with the body 40 when the diffuser is screwed as indicated at 58 into that body portion.

To facilitate this screwing effect, a hexagonally-shaped portion 59 may be furnished on the diffuser to receive a wrench. It is therefore seen that when the body portion 40, the nozzle 41 and the diffuser 42 are detachably joined together at the threads 48 and 58, the positional relationship between these parts is absolutely fixed and that by merely unscrewing the body portion at the threads 39 in the wall of the chamber 3, the entire unit, including the nozzle and the diffuser can be removed from the interior of the chamber, leaving merely a threaded opening in the wall. The purpose of this opening in connection with the conversion of the pump to deep well will be explained hereinafter.

There is a metal tube 60 (Figure 1) threaded at 23 to the left-hand half of the pump casing, this tube fitting snugly about the washer 56 and extending preferably to a position just beyond the shoulder or projection 54 but not covering up the opening 46. A confined annular space is thus presented about the outside surface of the diffuser 42. The tip 61 of the diffuser has a diameter somewhat less than the diametral size of the impeller inlet tube 20 and the space between the tube 60 and the diffuser 42 is in communica-

cation with the suction inlet of the pressure pump 18.

In addition to the large threaded openings 37, 39, the chamber 3 has a threaded opening 62 at the bottom side which is shown as receiving a plug 63. The purpose of this plug will be described hereinafter.

It is well-known that in order to provide an air cushion at the top of a pneumatic tank to supply continuous pressure to the stored water, some form of automatic air volume control must be employed by which air is introduced into the tank at a predetermined rate, dependent on the loss of air from the tank when the water is being discharged to the service pipes. For this purpose there is provided a copper tubing 64 passing through the wall of cylinder 60 and brazed thereto as indicated at 65, this tubing being flexible as indicated by its curvilinear shape in Figure 2 and inserted into a slidably fitted opening 66 formed in the vane plate. This opening communicates with an elbow 67 threadedly secured to the left-hand wall of the motor bracket 2. There is a pipe 68 which leads into the elbow through a Schrader valve 69 and is connected to an air volume control valve 70 of any suitable and well-known type secured to a pneumatic tank indicated at 71.

By means of a float mechanism within the tank which moves in accordance with changes in level of water and therefore represents the change in the amount of air at the top of the tank, a valve is opened to admit air to the pipe 68 and this air passes through the tube 64 and finally reaches the suction inlet of the pressure pump as explained hereinbefore.

The casting 28 is provided with a relatively small opening 72 at a position near the threaded opening 37 for receiving a pipe coupling 73 attached to a small conduit or pipe 74 leading to the pressure responsive switch 4 on the motor. As the pressure of the fluid in the chamber 3 exceeds a predetermined amount, this pressure is communicated to the fluid in the pipe 74 to cause the switch 4 to break the circuit leading to the motor 1. When water is drawn off at the pipe 36, which may be a service pipe or may lead to a pneumatic pressure tank so as to reduce the pressure of the fluid in the chamber 3, the reduction in pressure causes the switch 4 to become energized and reestablish the motor circuit. The gauge 35 has no automatic feature but is used simply to show the priming conditions of the pump in terms of the pressure of the fluid in the chamber 3.

The set up shown in Figure 1 is intended for shallow well use, i. e. for suction heads no greater than 20 to 25 ft. In order to adapt the pump structure to deep well operation, i. e. above 25 ft., it is obvious that the jet pump must be removed and placed down near the water in the well, preferably submerged, in order to combine the lifting effects of the jet pump with the suction effect of the pressure pump. For this purpose an accessory or adaptor is provided for replacing the jet pump and this accessory is shown in Figures 6 and 7. It consists mainly in a multi-shouldered tube of metal having a hexagon head 75 threaded as indicated at 76 to receive the delivery pipe 77 from the submerged jet pump. There is a threaded shoulder 78 for engaging the threads of the bore 39.

A second shoulder 79 is also provided having a groove 80 which receives a washer 81 similar to the washer 56. As shown in Figure 9, the washer

81 snugly fits against the cylinder 60 and, as in the case of the washer 56, serves to prevent any fluid from moving toward the left in the cylinder 60. It is obvious that when the tube accessory shown in Figure 6 is screwed into the casting 28, assuming that the jet pump 41, 42 has been previously removed, the opening 82 in the tube is directly in line with the axis of the cylinder 60 and therefore coaxial with the suction inlet of the pressure pump 18. Inasmuch as the washer 81 is positioned within the cylinder to the left of the tubing 64 and its Schrader valve, the air control device is not disturbed but is available for deep well use as for shallow well operation.

The plug 63 at the bottom of the chamber 3 is removed to receive the threaded end of a pressure pipe 83. The jet pump for deep well operation is usually positioned just below the level of the water in the well or other source of fluid and may comprise a nozzle 84 and a cooperating diffuser or venturi 85. The pressure pipe 83 is connected through an elbow 86 and a drop pipe 87 to a body casting 88 having a curved passageway which terminates at the nozzle 84. The tip of the nozzle is spaced a distance from the lower end of the diffuser 85 to leave an annular space 89 which communicates through passageways in the casting 88 to a suction compartment 90. This compartment is in communication through a pipe 91 with a foot valve structure 92 of any suitable and well-known type which terminates at the bottom in a strainer 93.

The diffuser 85 may comprise a tubing of hard fiber or metal and is detachably secured within a pipe 94, the latter being connected through an extension 95 and an elbow 96 to the delivery pipe 77.

It is therefore apparent that in order to change over the shallow well structure as shown in Figures 1 and 8 to deep well operation it is necessary to replace the jet pump elements 41, 42 which are normally contained within the chamber 3, by the tubular adaptor shown in Figure 6 and then remove the plug 63 and substitute therefor the pressure pipe 83. In removing the shallow well jet pump unit, it is simply necessary to unscrew the member 40 to leave the opening 39, at which time the jet pump can be freely withdrawn through the opening without disturbing the casing or chamber 3 and also without affecting the air control valve connection 64.

The operation of the pump is essentially the same for shallow and deep well use except for the change in position of the jet pump. Combined water and air entering the suction pipe 45 flows past the outer surface of the nozzle 41 into the space 51, thence through the venturi 42 into the suction inlet of the pressure pump. The water is delivered under pressure at the discharge openings of the vane plate 26 into the combined air separator and priming chamber 3. The separated air rises to the top of the chamber and flows out through the main discharge pipe 36 together with the service water. This pipe may be connected to a pneumatic pressure tank and the air contained in the water collects at the top of the tank to provide a pneumatic cushion. The water from which air has been separated flows downwardly through the opening 46 to the bore in the nozzle 41 and creates a suction effect between the nozzle and the diffuser sufficiently intense that when added to the suction of the pressure pump serves to lift water through the suction pipe 45.

In the event that for any reason the air collected at the top of the pneumatic pressure tank 75

is not sufficient to provide the necessary pressure to service the water, the automatic air volume control 70 will operate to admit additional air through the tube 64 and the Schrader valve 69 into the cylinder 60. This air in traveling through the pressure pump, is separated in the chamber 3 from the water, finally passing out through the pipe 36 to the tank.

It will be noted that the jet pump unit is contained entirely within the chamber 3, or rather, this chamber has been greatly enlarged so as to extend to the rear of the jet pump. Moreover, the main discharge pipe 36 is taken out from the chamber, as close to the top as possible and the nozzle 41 of the jet pump is positioned remote from the main discharge pipe.

From the structural standpoint, the improved pump offers distinct advantages in that not only can the jet pump be readily removed from the casing in the manner described, but the pressure pump can also be readily detached from the casing 3 for inspection or replacement purposes. This is readily done by removing or loosening the bolts or cap screws 31 (assuming that the pipe coupling 73 leading to the switch 3 has also been disconnected) at which time the motor bracket 2 and the motor can be moved relative to the casing 3, carrying with it the entire pressure pump structure including the cylinder 60. In order to obtain access to the cap screws 31, it will be necessary to remove the sheet metal cover 9 by loosening the screws 11. It will be noted that the cylinder 60 can readily slide over the round washer 58 of the diffuser. The pump casing can then be easily disassembled by removing the cap screws 27.

Inasmuch as the end of the tube 64 is brazed in the cylinder 60, it might be difficult to insert the opposite end of the tubing into the opening 66 in the vane plate and for this reason it is desirable to make the tubing 64 of flexible material as indicated, particularly in Figure 2, so that regardless of the peripheral position of the brazed end with respect to the opening 66, the tubing can be readily inserted into the opening.

When the pump is arranged for deep well operation, including the insertion of the tube element 79 (Figure 6), and assuming that the jet pump body 88 is submerged in the water of the well, the water passes through the foot valve 92 into the spaces 90 and 89, thence up through the diffuser 85 to the inlet conduit 20 of the pressure pump. Air is separated from the water in the chamber 3 as explained hereinbefore and the treated water flows to the bottom of the chamber and through the pipe 83 to the nozzle 84 in order to enhance the suction effect between the nozzle and the diffuser. Thus the submerged jet pump assists the pressure pump in lifting the water through the deep well pipes and the separated air and water flow out through the service pipe 36. It will be noted that the air control device functions equally well for deep as for shallow well operation because in both cases the pipe 64 is in communication with the suction side of the pressure pump.

It will be further observed that the position within the chamber 3 at which the separated air collects, namely at the top of the chamber, is remote from the position at which water is withdrawn from the chamber to drive the submerged jet pump, so that the water arriving at the nozzle 84 has had the objectionable part of the air removed. The pressure pump will therefore never become air bound.

It is also evident that the chamber 3, in addi-

tion to serving as an effective air separator, serves the function of a priming chamber to the extent that a considerable head of water is always maintained on the pressure pump, assuming that the chamber is initially filled with water and this last mentioned condition is assured by the use of the foot valve 92 which prevents any water from dropping out of the pipes 11, 83. The suction pipe 45 of the shallow well installation is also preferably provided with a foot valve (not shown) for the reason given immediately above.

It will be understood that various modifications and arrangements in structure could be made without departing from the spirit of my invention and, accordingly, I desire to comprehend such modifications and substitutions of equivalents as may be considered to come within the scope of the appended claims.

I claim:

1. A pumping apparatus comprising a pressure pump having inlet and discharge openings, a removable jet pump presented to the inlet opening of the pressure pump, a combined air separator and priming chamber communicating with the discharge opening of the pressure pump and with the jet pump in order to supply substantially air free water to the jet pump, a cylinder surrounding a portion of the jet pump and coaxial with the inlet opening of the pressure pump leaving a space between the cylinder and the jet pump, and means including a conduit fixedly secured to said cylinder for supplying predetermined amounts of air to the space between the cylinder and the jet pump, the size of the inlet opening of the pressure pump being greater than the size of the jet pump in order to leave an annular space through which the introduced air can flow into the pressure pump, and said air-introducing conduit being adapted to remain fixed to said cylinder when the jet pump is being removed from said cylinder.

2. A pumping apparatus comprising a pressure pump having inlet and discharge openings, a removable jet pump formed of a nozzle and a cooperating diffuser, said diffuser being presented to the inlet opening of the pressure pump, a combined air separator and priming chamber communicating with the discharge opening of the pressure pump and with the nozzle of the jet pump, means for supplying the space between said nozzle and diffuser with fluid, a main discharge pipe connected to said chamber, the jet pump being contained within the chamber, a cylindrical member surrounding a portion of the jet pump to leave a space communicating with the inlet opening of the pressure pump beyond the diffuser, and means including a conduit fixedly secured to said cylinder for supplying predetermined amounts of air to the space within said member in order to provide pneumatic pressure effects to the water discharged through said main discharge pipe, and said air-introducing conduit being adapted to remain fixed to said cylinder when the jet pump is being removed from said cylinder.

3. In a convertible deep and shallow well pump, the combination of a distribution casing having a pair of spaced, opposed walls, a pressure pump operatively mounted in one of the walls and having a suction inlet and a pressure outlet, said outlet communicating with said casing, a pair of openings in the other of said walls, a fitting in one of said openings in line with the suction inlet of the pump, and a removable plug in the other of said openings, a tubular member extending

over at least a portion of said casing and supported at one end by the pump, a removable jet pump assembly contained, at least in part, within the tubular member and presented to the suction inlet of the pressure pump, said jet pump assembly comprising a nozzle and a diffuser in spaced relationship and supported at one end by said fitting, said nozzle being in communication with the interior of said casing and the space between said nozzle and diffuser being connected to an external source of fluid through said fitting, and a main discharge opening in said casing, said tubular member being of greater size than the jet pump assembly to leave an annular space therebetween a sealing ring in said space, positioned between the member and the jet pump, near one end of the jet pump, that portion of the annular space between the sealing ring and the pressure pump being in communication with the suction inlet of the pressure pump, and means for supplying predetermined amounts of air from the atmosphere into said portion of the annular space between the sealing ring and the pressure pump in order to present this air to the suction side of the pressure pump.

4. A pumping apparatus comprising a pressure pump having inlet and discharge openings, a jet pump formed of a nozzle and a diffuser in spaced relationship, said diffuser being presented to the inlet opening of the pressure pump, a combined air separator and priming chamber communicating directly with the discharge opening of the pressure pump and with said nozzle, means for supplying the space between the nozzle and diffuser with fluid from a source of fluid outside of the chamber, a main discharge pipe connected to said chamber, the jet pump being contained within the chamber, a tubular member surrounding at least a portion of the jet pump and spaced therefrom, said member being supported at one end by the pressure pump, the space between the member and jet pump being in communication with the inlet opening of the pressure pump, and means including a tubing secured to said tubular member for supplying said space with predetermined amounts of air from the atmosphere.

5. In a convertible deep and shallow well pump, the combination of a distribution casing having a pair of spaced, opposed walls, a pressure pump operatively mounted in one of the walls and having a suction inlet and a pressure outlet, said outlet communicating with said casing, a pair of openings in the other of said walls, a fitting in one of said openings in line with the suction inlet of the pump, and a removable plug in the other of said openings, a tubular member extending at least over a portion of said casing and supported at one end by the pump, a removable jet pump assembly supported by said fitting and mounted, at least in part, within the tubular member and presented to the suction inlet of the pressure pump, said jet pump comprising a nozzle and a diffuser in spaced relationship, said nozzle being in communication with the interior of said casing and the space between said nozzle and diffuser being connected to an external source of fluid through said fitting, a main discharge opening in said casing, said tubular member being in communication with the suction inlet of the pressure pump, and means including a conduit secured to said tubular member for introducing controllable amounts of air to the interior of said

11

member in order that the air will flow into the suction side of the pressure pump.
